(57) **CLAIM**

The ornamental design for an inlay piece set, as shown and described.

DESCRIPTION

FIG. 1 is an enlarged top plan view of a wavy rhombus piece of the inlay piece set.

FIG. 2 is a side view thereof.

FIG. 3 is an enlarged top plan view of a wavy Y isometric piece of the inlay piece set.

FIG. 4 is a side view thereof; and,

FIG. 5 is a perspective view of the wavy rhombus piece and the wavy Y isometric piece of the inlay piece set.

The broken lines are for illustrative purposes only and form no part of the claimed design.

1 Claim, 1 Drawing Sheet
